UNITED STATES PATENT OFFICE.

ALBERT C. MENTZER AND ROBERT E. DUPREY, OF HUDSON, MASSACHUSETTS.

LOAD-HANDLING APPARATUS.

1,276,674.

Specification of Letters Patent. Patented Aug. 20, 1918.

Application filed April 3, 1915. Serial No. 18,993.

To all whom it may concern:

Be it known that we, ALBERT C. MENTZER and ROBERT E. DUPREY, citizens of the United States, residing at Hudson, in the county of Middlesex and State of Massachusetts, have invented new and useful Improvements in Load-Handling Apparatus, of which the following is a specification.

This invention relates to load handling apparatus, the broad object in view being to greatly facilitate the handling of merchandise and materials of all kinds, and effect a valuable saving of time, enabling an ordinary motor truck, for example, to make many more trips per day than may now be accomplished where the truck has to be loaded and unloaded in each trip back and forth between the source of supply and the point of delivery.

More specifically stated, the object of the present invention is to provide means whereby a loaded body may be quickly transferred from a stationary supporting base to a wheeled supporting base and vice versa, the said wheeled supporting base resembling in its general character a truck. By means of the construction hereinafter described, the wheeled supporting base may be quickly loaded and unloaded by cheap help, requiring only a few minutes and therefore enabling a merchant, for example, to keep the truck moving from place to place.

With the above and other objects in view, the invention consists in the novel construction, combination and arrangement of parts, as herein described, illustrated and claimed.

In the accompanying drawings:—

Figure 1 is a side elevation showing a stationary supporting base or stand, a wheeled supporting base or truck, and the transferable body adapted to be slid from one supporting base to the other, said body being shown as resting upon the stationary supporting base.

Fig. 2 is a similar view showing the body after the same has been transferred to the wheeled supporting base.

Fig. 3 is a similar view showing the body at about a middle point in its movement from one supporting base to the other.

Fig. 4 is an underneath perspective view of the body.

Fig. 5 is a plan view of the body support.

Fig. 6 is a vertical longitudinal section illustrating the manner of using the draft

rope and windlass and also illustrating the function of the range adjusting screws.

Referring to the drawings A and B designate supporting bases, the supporting base A being shown in the form of a stationary stand preferably of stout construction so as to support a heavy load. The supporting base B is shown in the form of a truck provided with carrying wheels 1.

The supporting base B may consist either of a simple hand operated truck or a truck adapted to be moved by draft animals or a motor truck of the present day type.

Mounted upon each of the supporting bases A and B is a body support 2 while 3 designates a load carrying body which is transferable from one body support to the other. Each body support 2 is pivotally mounted at 4 on its supporting base thereby adapting said body support to tilt for the purpose of enabling the adjacent ends of two abutting body supports to be brought into the same horizontal plane in order to facilitate the transfer of the body 3 by a sliding movement from one body support to the other.

The transferable body 3 is also of stout construction as shown in Fig. 4, the same comprising a platform 5, transversely extending knees 6 and longitudinally extending stringers 7 parallel to each other and connecting said knees, 8 designating metal-shoes or runners secured to the bottom faces of the stringers 7 and having their opposite end portions curved upwardly as shown at 9 in the form of ordinary sleigh runners in order to facilitate the sliding of the transferable body from one body support to another.

In order to reduce friction to a minimum and enable the transferable body to be quickly slid with its load from one supporting base to the other and in order also to properly guide said transferable body, each body support 2 is provided with flanged guide rails 10, the flanges of which extend upwardly so as to embrace the stringers 7 and runners or shoes 8 of the transferable body. Arranged between the flanges of the rails 10 and located at suitable intervals apart in the length thereof are anti-friction elements 11 which may consist of rollers or balls adapted to directly contact with the shoes or runners 8. Therefore, the transferable body rolls easily upon said anti-friction

- elements while being pushed or drawn from one supporting base to the other.
- It is also desirable to provide in connection with each supporting base, a windlass 5 12 adapted to be operated by a hand crank 13, 14 designating a flexible element such as a rope or cable which is fastened to the body of the windlass and is adapted to be wound thereon, said flexible draft cable or element 10 being terminally provided with a hook 15 adapted to engage a hook 16 at one end of the transferable body, two of said hooks 16 being preferably employed and arranged at opposite ends of the body to enable the latter 15 to be drawn by means of the windlass in either direction. The windlass may be located centrally of the supporting base or at one end thereof as may be preferred and as illustrated in the drawings.
- 20 The adjacent ends of the body supports 2 are adapted to be sustained at the same or approximately the same level for the purpose above stated by means of supporting screws 17 which have a threaded engagement with the supporting base in each case, the upper ends of said screws serving as stops and supports for the adjacent ends of the tilting body supports. The purpose of this portion of the invention is to enable the body 25 support of either supporting base to be adjusted or tilted at the necessary angle to bring the same into a common level with the adjacent end of the other body support in accordance with the weight of the load imposed on the wheeled supporting base, it being understood that in the case of a motor truck or the like, the body thereof varies in elevation in accordance with the load thereon.
- 30 From the foregoing description, taken in connection with the accompanying drawings, it will now be understood that if the body 3 has been loaded either upon a stationary supporting base or a wheeled supporting base, said load carrying body may be easily 35 transferred with a minimum amount of effort, in proportion to the load thereon, by merely pushing, drawing or otherwise sliding said transferable body from one supporting base to the other or from one body support to the other. It requires but a few minutes to effect the transfer of the load carrying body and thereby greatly reduces the time during which a motor truck, for 40 example, remains idle. In other words, it is not necessary to unload the truck in the
- manner usually employed but all that is required is to shift the entire load by means of the load carrying body from one supporting base to the adjoining supporting base. 60
- What we claim is:—
1. In load handling apparatus, the combination of two supporting bases one of which is movable in relation to the other, tilting body supports medially pivoted upon and supported by said bases and each embodying parallel sets of guide rails, and rollers journaled between said guide rails and lying below the top edges thereof, and a load carrying body comprising longitudinal 65 bottom stringers, and runner shoes extending longitudinally of and secured to said stringers and having their opposite end portions recurved in an upward direction and secured to said load carrying body at a 70 higher elevation than the main bodies of the runner shoes, said stringers and shoes being positioned and slidable between said guide rails and upon said rollers.
2. In load handling apparatus, the combination of two supporting bases one of which is movable in relation to the other, tilting body supports medially pivoted upon and supported by said bases and each embodying parallel sets of guide rails, and rollers journaled between said guide rails and lying below the top edges thereof, and a load carrying body comprising longitudinal 75 bottom stringers, runner shoes extending longitudinally of and secured to said stringers and having their opposite end portions recurved in an upward direction and secured to said load carrying body at a higher elevation than the main bodies of the runner shoes, said stringers and shoes being positioned and slidable between said guide rails and upon said rollers.
3. In load handling apparatus, the combination of two supporting bases one of which is movable in relation to the other, tilting body supports medially pivoted upon and supported by said bases and each embodying parallel sets of guide rails, and rollers journaled between said guide rails and lying below the top edges thereof, and a load carrying body comprising longitudinal 80 bottom stringers, runner shoes extending longitudinally of and secured to said stringers and having their opposite end portions recurved in an upward direction and secured to said load carrying body at a higher elevation than the main bodies of the runner shoes, said stringers and shoes being positioned and slidable between said guide rails and upon said rollers.
4. In load handling apparatus, the combination of two supporting bases one of which is movable in relation to the other, tilting body supports medially pivoted upon and supported by said bases and each embodying parallel sets of guide rails, and rollers journaled between said guide rails and lying below the top edges thereof, and a load carrying body comprising longitudinal 85 bottom stringers, runner shoes extending longitudinally of and secured to said stringers and having their opposite end portions recurved in an upward direction and secured to said load carrying body at a higher elevation than the main bodies of the runner shoes, said stringers and shoes being positioned and slidable between said guide rails and upon said rollers.
5. In load handling apparatus, the combination of two supporting bases one of which is movable in relation to the other, tilting body supports medially pivoted upon and supported by said bases and each embodying parallel sets of guide rails, and rollers journaled between said guide rails and lying below the top edges thereof, and a load carrying body comprising longitudinal 90 bottom stringers, runner shoes extending longitudinally of and secured to said stringers and having their opposite end portions recurved in an upward direction and secured to said load carrying body at a higher elevation than the main bodies of the runner shoes, said stringers and shoes being positioned and slidable between said guide rails and upon said rollers.
6. In load handling apparatus, the combination of two supporting bases one of which is movable in relation to the other, tilting body supports medially pivoted upon and supported by said bases and each embodying parallel sets of guide rails, and rollers journaled between said guide rails and lying below the top edges thereof, and a load carrying body comprising longitudinal 95 bottom stringers, runner shoes extending longitudinally of and secured to said stringers and having their opposite end portions recurved in an upward direction and secured to said load carrying body at a higher elevation than the main bodies of the runner shoes, said stringers and shoes being positioned and slidable between said guide rails and upon said rollers.
7. In load handling apparatus, the combination of two supporting bases one of which is movable in relation to the other, tilting body supports medially pivoted upon and supported by said bases and each embodying parallel sets of guide rails, and rollers journaled between said guide rails and lying below the top edges thereof, and a load carrying body comprising longitudinal 100 bottom stringers, runner shoes extending longitudinally of and secured to said stringers and having their opposite end portions recurved in an upward direction and secured to said load carrying body at a higher elevation than the main bodies of the runner shoes, said stringers and shoes being positioned and slidable between said guide rails and upon said rollers, means for tilting said body supports to bring the adjacent ends thereof into alignment with each other, and means for actuating said load carrying body comprising a windlass located at one end of one body support, a cable thereon, another windlass having its axis coincident with the pivotal center of the other body support, and a cable on the last named windlass. 105
